UNITED STATES PATENT OFFICE.

PAUL S. PITTENGER, OF PHILADELPHIA, PENNSYLVANIA, ASSIGNOR TO H. K. MULFORD COMPANY, OF PHILADELPHIA, PENNSYLVANIA, A CORPORATION OF PENNSYLVANIA.

HYPODERMIC PACKAGE AND METHOD OF USING THE SAME.

Application filed February 24, 1923. Serial No. 620,962.

In the past much trouble has been experienced in utilizing medicinal preparations hypodermically when these were dispensed in ampules or stoppered vials, owing 5 to the fact that it was difficult if not frequently impossible to transfer such preparations from the ampule or vial to a hypodermic syringe, without destroying the sterility of or contaminating said preparation. This was due to the fact that when 10 the needle of the hypodermic syringe was passed through the stopper of the vial into the interior of the same, the operation of the plunger of the syringe would not cause 15 the liquid preparation to flow out of the vial into the syringe barrel because of the vacuum produced, and it was usually necessary for the operator to reciprocate the plunger a number of times in order to withdraw 20 even a small portion of the liquid. If in the case of an ampule the neck was broken or the stopper removed from the vial so that the medicinal preparation therein could be freely drawn into the syringe, then 25 the entrance of atmospheric air contaminated the liquid.

One object of my invention, therefore, is to provide a hypodermic set or outfit including a hypodermic syringe and one or more 30 ampule-vials of which the latter shall contain a medicinal preparation capable of being withdrawn into the barrel of said syringe by one operation of its plunger without being contaminated by the air or otherwise.

A further object of the invention is to 35 provide a novel method of using or manipulating the above hypodermic outfit.

Another object of my invention is to provide as a new article of manufacture an ampule-vial containing a medicinal preparation 40 for hypodermic use so put up as to permit of its being withdrawn into a hypodermic syringe without bacterial or other contamination.

I also desire to provide an ampule-vial with a novel form of stopper and protective device therefor.

These objects and other advantageous ends I attain as hereinafter set forth, reference 45 being had to the accompanying drawings, in which;

Fig. 1 is a side elevation of a hypodermic syringe which may form part of and be used in connection with my invention;

Fig. 2 is a side elevation of the ampule-vial forming part of my invention; and,

Fig. 3 is an enlarged vertical section of a portion of the ampule-vial shown in Fig. 2.

In the above drawings 1 represents the barrel or cylinder of a well known form of 55 hypodermic syringe which has a plunger 4 actuated by a piston rod 3 provided with a cross bar or handle 5. Said syringe includes a hypodermic needle 8 mounted on its nozzle or outlet.

The above described syringe may conveniently be employed to administer the sterile liquid from an ampule-vial 10 in the form of an elongated glass or other container having its outlet closed by a stopper 11, which in accordance with my invention, is centrally perforated for a portion of its length to provide a guideway for the needle 8 of the hypodermic syringe when the latter is introduced for the purpose of withdrawing the liquid contents α of said ampule-vial. In order to prevent accumulation of dust, bacteria or any other material in the central passage 12 of the stopper 11, I mount in it a tightly fitting stem 13 having 70 a convex head 14 extending over and serving as a cover for the outer end of the stopper 11. It is to be noted that after the material α has been placed in the ampule-vial, the stopper inserted and the stem 13 75 with its cover placed in the passage 12, the whole is sterilized.

Further in accordance with my invention, the capacity of the barrel of the syringe and that of the ampule-vial 10 are made to 80 bear a definite relation to each other, and I have found that to obtain the best results, the ampule-vial should have a capacity in the neighborhood of one-third more than that of the syringe barrel, though I may 85 vary this proportion to some extent without departing from my invention. Moreover the ampule-vial, instead of being completely filled with the medicinal preparation α is made to contain a quantity thereof substantially equal in volume to the capacity of the syringe barrel, so that for example, if the ampule-vial 10 be designed to contain 5 cc. of liquid and to have an air filled space γ 90 2.5 cc. in volume, the barrel of the syringe 105 would have a capacity of substantially 5 cc. The size of the air space is very essential, since if it is too small it will not permit of

ready ingress of 5 cc. of air, while if too large it will not exert sufficient pressure to completely empty the barrel at one operation when the syringe plunger is drawn out at the ordinary speed.

With the parts constructed and proportioned as above described, when it is desired to withdraw the material from the ampule-vial, the plunger 4 of the syringe is drawn out into the position shown in Fig. 1, after which the protective cover 14 with its stem 13 is withdrawn from the passage 12 of the stopper 11 and the needle 8 of the syringe is forced through the unperforated portion of said stopper into the cavity of the ampule-vial. The air in the syringe barrel is now forcibly ejected into the ampule-vial and is compressed therein by movement of the syringe plunger 4 toward the outlet end of the barrel. When the plunger 4 is moved toward the closed end 2 of the syringe barrel, the air which has been compressed in the space y expands to force the liquid x through the needle into the syringe until this is filled with liquid and without further or repeated operation of said plunger, after which the syringe may be used in the well understood manner to administer the same.

It is to be noted that if the air space in the ampule-vial be proportionately too small, it will not permit of the ready entrance of 5 cc. of air and if it be too large, the air will not be sufficiently compressed within it to completely eject all of the liquid when the syringe plunger is drawn out at the ordinary speed.

By the procedure described, a single operation of the syringe piston in opposite directions, suffices to completely withdraw all of the liquid from the ampule-vial so that much time is saved and there is no necessity to contaminate said liquid by prolonged and repeated attempts to withdraw the same.

Moreover I am enabled to transfer the contents of a liquid filled ampule-vial to the barrel of a hypodermic syringe with a minimum danger of contamination, and it is obvious that if the needle 8 is sterile, it may be forced through the stopper 11 of the ampule-vial without being contaminated, since the stem 13 has prevented the entrance into the guide passage 12 of any contaminating material.

I claim:

1. A hypodermic set comprising an ampule-vial; a medicinal liquid filling substantially two-thirds of the capacity of the ampule-vial; and a hypodermic syringe having a capacity substantially equal to that of the liquid-filled space of the ampule-vial to 55 permit of the transfer of the liquid from the latter to said syringe, said ampule-vial being sealed and having a part adapted to be penetrated by the needle of the hypodermic syringe whereby the air in the syringe may 60 be forced into the ampule-vial to cause the subsequent displacement of the liquid into the syringe.

2. As a new article of manufacture, an ampule-vial containing a medicinal liquid and having a part adapted to be penetrated by the needle of a hypodermic syringe, a substantial proportion of the cavity of said vial being unoccupied by said liquid and adapted to receive sufficient air under pressure to permit withdrawal of substantially 70 the entire quantity of contained liquid by said syringe after insertion of said needle by a single withdrawal of the plunger of 75 said syringe.

3. As a new article of manufacture, an ampule-vial containing a liquid medicinal preparation, a stopper for the ampule-vial having a needle guiding passage extending only part way through it and having an imperforate portion inwardly of the guide passage whereby the stopper normally closes the outlet of said ampule-vial and means independent of the needle to be inserted through the guide passage for maintaining 80 the passage in sterile condition and comprising a stem detachably mounted in said passage.

4. As a new article of manufacture, an ampule-vial containing a liquid medicinal preparation, a stopper for the ampule-vial having a needle guiding passage extending only part way through it and having an imperforate portion inwardly of the guide passage whereby the stopper normally 95 closes the outlet of said ampule-vial, means independent of the needle to be inserted through the guide passage for maintaining the passage in sterile condition and comprising a stem detachably mounted in said passage, and a head on said stem extending over 100 the entire outer face of the stopper.

PAUL S. PITTINGER.
